OIL BURNER

Gustave C. Peter, Wauwatoza, Wis.

Application January 20, 1943, Serial No. 472,930

4 Claims. (Cl. 126—93)

This invention relates generally to oil burners, desirably those of the space heater type utilizing a fire pot within a combustion chamber. More particularly, the present improvements are concerned with a device, applicable to such burners, by which to provide an auxiliary air supply for support of the combustion. In the accomplishment of this end I utilize materials and parts which are durable, inexpensive, simple, and adaptable to existing burners of various makes, sizes, etc. When installed and in use, the auxiliary supply of air furnished by the present device will produce a more efficient combustion of the fuel, will assure a satisfactory operation of the burner even when the stack draft is as low as .01 inch, water gauge, will reduce substantially the stack losses (wet and dry gases), and accomplish all this without accumulation of soot and carbon in any appreciable amount due to more nearly complete combustion of the fuel. To attain these and other objects, as will hereinafter appear, I employ the device of which a preferred embodiment is illustrated in the accompanying drawing, wherein—

Figure 1 is a perspective view of a conventional space heater with certain of the walls broken away to expose the combustion chamber and an enclosed fire pot with the present device installed in place therewithin;

Fig. 2 is a longitudinal section through the device in its entirety, taken on line 2—2 of Fig. 1;

Fig. 3 is a top plan view of the damper fitted to the upper end of the device; and

Fig. 4 is a transverse section taken on line 4—4 of Fig. 2.

As shown best in Fig. 1, a fire pot A of conventional type is disposed within a housing B forming a combustion chamber having a top closure 5. The pot may be equipped with the usual fire ring 6 formed with a large central opening 7. Through ports 8 formed in the walls of the pot air is admitted thereto to support combustion therewithin. A pipe connection (not shown) leads from the pot to a source of fuel supply either within or outside of a cabinet C enclosing the combustion chamber to afford an attractive appearance for the space heater in its entirety. It is with an oil burner of this general type that the present device forming my improved auxiliary air supply may be used to advantage.

Referring now to Fig. 2, a pair of tubular sections 10 and 11 are slidably interfitted to provide an extensible tube D. One of these sections, here shown as the inner one 10, is extended

through an opening 12 formed in the closure top 5 of the combustion chamber, its upper end being flanged as at 13 to provide a head against which is rested a circular plate 14 having at its periphery a plurality of lugs 15 which are reversely bent to underlie the head whereby to secure the plate fixedly in place. This plate which is formed with a concentric arcuate slot 16 furnishes a seat for a rotatable disk 17 to which it is connected as by an axial rivet 18. From the rotatable disk is radially extended a lug 19 forming an operating finger piece therefor, and in its body is a concentric arcuate slot 20 adapted to register with the plate slot 16 when in proper rotative position relative thereto. By means such as this I provide a simple, inexpensive and dependable form of damper at the top end of the tube D, located upon the upper face of the closure top 5, and providing, in effect, a head which rests thereupon to afford a sustaining support for the tube which depends through the opening 12 into the combustion chamber, preferably at a point which is substantially axially thereof.

25 The tube D is joined at its lower end to the neck 25 of a bell E. To accomplish this, the interfitting faces of the lower tubular section 11 and neck may be tapered slightly to promote a tight fit, and a threaded set screw 26 be entered through the neck for adjustable bearing against the tube. The bell which flares out widely is formed peripherally with a vertical face 27, and with a plurality of depending bosses 28 (three being shown), each having a vertical bore 29 which opens out at the top upon a seat 30. A bell of this description is adapted for fitting within a base F having a horizontal bottom 25 surrounded by a peripheral flange 36 formed with a vertically extending circular face 37.

30 Through the base bottom, in register with the bores 28, are openings through each of which is extended a pin 38 having heads at its opposite ends, one engaging the underside of the base and the other the bell seat 30. In some such way as this the bell may be joined to the base, immovably and inseparably, with the two faces 27 and 37 spaced slightly apart evenly and uniformly to provide an upwardly facing circular aperture through which air may be discharged in the form of an annular stream. Feet 40 are shown as depending from the base for resting upon the bottom of the pot whereby the device in its entirety may be supported in an elevated position relative thereto. In practice, the bell and base may each be produced from a

ferrous metal, as by a casting operation, and little or no finishing is required to adapt them for combination with each other, and for assuring an upwardly facing annular discharge opening therebetween of a desired width which, for best results, may be about $\frac{1}{4}$ of an inch.

To install in a conventional space heater, an opening is formed, preferably centrally, in the top of the combustion chamber permitting the upper tubular section 10 to be inserted therethrough for interfitting with the other section 11 which upstands from the bell-base when properly positioned upon the pot bottom. The two tubular sections will adjust themselves slidingly as required by the height of the closure top of the combustion chamber. In operation, the flames rising from the fuel under combustion will, in time, heat the device, particularly the extensible tube through the region opposite the bracket (shown in Fig. 1) to the point of acquiring a cherry red color. To support such combustion the air supply received through the pot wall ports 8 is augmented very appreciably by that which is admitted through the tube D and therein raised to a high temperature before discharge in an upward direction in the form of an annular stream at a point close to the bottom of the burner pot, centrally thereof, and to the inside of the flames rising therewithin. Inasmuch as conditions vary greatly in different installations, it is desirable to make one individual, and final, adjustment in each case, this being done by setting the damper to admit air in the volume required for best results. For example, the stack draft may be anywhere from .01 inch to .02 inch, and at the damper the draft may be less than .01 inch, water gauge. Under such conditions the secondary or auxiliary supply of air made possible by the present apparatus will produce a more complete combustion of the fuel, without any accompanying danger of soot and carbon accumulation. In cases of higher stack draft the damper adjustment will probably be different than that suggested in the above example, but in all instances, according to present experience, a greater efficiency and more satisfactory operation is attained by use of my apparatus which assures an ample supply of secondary air delivered in a highly heated condition centrally of the burner at a point close to its bottom and discharged straight upwardly in the form of an annular stream interiorly of the ascending flames whose remaining oxygen supply is delivered externally and in a relatively cool state. My device, therefore, comprises at the lower tube end a diffuser from which preheated air issues upwardly in a volume sufficient to produce substantially complete combustion of the fuel even under conditions of relatively low stack draft.

I claim:

1. In combination with an oil burner of the type in which is comprised a housing forming a combustion chamber with a top closure, and within the chamber a fire pot having walls with ports through which is admitted a primary supply of air, means providing an auxiliary air supply to support combustion within the pot comprising an extensible tube depending from the top closure of the combustion chamber and open to the atmosphere thereabove, a head incorporating a damper at the upper tube end in overlying relation to the closure top whereby to support the tube therefrom, and an air diffuser spaced from the pot wall and resting upon the

5 pot bottom and joined to the lower end of the tube, the diffuser including a circular base with side walls and spaced from the side walls of the pot and a bell immovably united to the base having a peripheral face confronting in closely spaced relation the peripheral face of the base walls whereby to define with said base an upwardly facing annular aperture through which air may be discharged in an annular column centrally and vertically at the base.

10 2. In combination with an oil burner of the type in which is comprised a housing forming a combustion chamber with a top closure, and within the chamber a fire pot having walls with ports through which is admitted a primary supply of air, means providing an auxiliary air supply to support combustion within the pot comprising a tube depending from the top closure of the combustion chamber and open to the atmosphere thereabove, a head at the upper tube end in overlying relation to the closure top whereby to support the tube therefrom, and an air diffuser spaced from the pot wall and resting upon the pot bottom and joined to the lower end 15 of the tube, the diffuser including a base with side walls and a bell immovably united to the base having a peripheral face confronting in closely spaced relation the peripheral face of the base walls and spaced from the side walls 20 of the pot whereby to define with said base an upwardly facing annular aperture through which air may be discharged in an annular column centrally and vertically at the base.

25 3. In combination with an oil burner of the type in which is comprised a housing forming a combustion chamber with a top closure, and within the chamber a fire pot having walls with ports through which is admitted a primary supply of air, means providing an auxiliary air supply to support combustion within the pot comprising a tube depending from the top closure of the combustion chamber and open to the atmosphere thereabove, a head at the upper tube end in overlying relation to the closure top 30 whereby to support the tube therefrom, and an air diffuser spaced from the pot wall and resting upon the pot bottom and joined to the lower end of the tube, the diffuser including a base with side walls and a bell immovably united to the base having a peripheral face confronting in closely spaced relation the peripheral face of the base walls and spaced from the side walls 35 of the pot whereby to define with said base an upwardly facing annular aperture through which air may be discharged in an annular column centrally and vertically at the base.

40 4. In combination with an oil burner of the type in which is comprised a housing forming a combustion chamber with a top closure, and within the chamber a fire pot having walls with ports through which is admitted a primary supply of air, means providing an auxiliary air supply to support combustion within the pot comprising a tube depending from the top closure of the combustion chamber and open to the atmosphere thereabove, a head at the upper tube end in overlying relation to the closure top 45 whereby to support the tube therefrom, and an air diffuser spaced from the pot wall and resting upon the pot bottom and joined to the lower end of the tube, the diffuser including a base, feet depending from the base to rest upon the pot bottom whereby to support the base in an elevated position thereupon, walls extending upwardly from the base defining therewith a space open only at the top, a bell surmounting the base 50 having peripheral walls in closely spaced relation to the walls of the base and spaced from the side walls of the pot and providing with said base a closure and defining therewith a narrow, continuously extending, upwardly facing, annular aperture through which air may be discharged in an annular column centrally and vertically at the base, and means uniting the bell immovably to the base.

55 5. In combination with an oil burner of the type in which is comprised a housing forming a combustion chamber with a top closure, and within the chamber a fire pot having walls with ports through which is admitted a primary supply of air, means providing an auxiliary air supply to support combustion within the pot comprising a tube depending from the top closure of the combustion chamber and open to the atmosphere thereabove, and an air diffuser spaced from the pot wall and resting upon the pot bottom 60 and joined to the lower end of the tube, the

diffuser including a base with means depending therefrom for engagement with the pot bottom to support the base in elevated position thereupon, a bell surmounting the base and provided with means depending therefrom for engagement and connection with the base to support the bell fixedly in elevated position thereupon,

and coating walls on the base and bell spaced from the side walls of the pot and defining between them an upwardly facing annular aperture through which air may be discharged in an annular column centrally and vertically at the base.

5 GUSTAVE C. PETER.
